Primary Examiner — Mehri F Bajoul(74) *Attorney, Agent, or Firm* — Bryce D. Miracle, Esq.(57) **CLAIM**

The ornamental design for an airmail box, as shown and described.

DESCRIPTION

FIG. 1 is a front perspective view of the airmail box showing the new design;

FIG. 2 is a bottom perspective view thereof;

FIG. 3 is a top plan view thereof;

FIG. 4 is a front elevation view thereof;

FIG. 5 is a rear elevation view thereof;

FIG. 6 is a left-side elevation view thereof; and,

FIG. 7 is a right-side elevation view thereof.

The broken lines shown in the drawings depict portions of the airmail box that form no part of the claimed design.

1 Claim, 2 Drawing Sheets(56)
